Rees Davis*

By Gundohl Parker & Carlson Atlys

UNITED STATES PATENT OFFICE.

REES DAVIS, OF CHICAGO, ILLINOIS.

DESIGN FOR A DOLL.

Application filed April 22, 1922. Serial No. 1,916. Term of patent 3½ years.

To all whom it may concern:

Be it known that I, REES DAVIS, a citizen of the United States, residing at Chicago, in the county of Cook and State of Illinois, have invented a new, original, and ornamental Design for a Doll, of which the following is a specification; reference being had to the accompanying drawing, forming part hereof, wherein the figure is a front perspective view of the doll.

I claim:

The ornamental design for a doll, as shown.

REES DAVIS.
